US00D924268S

(12) **United States Design Patent** (10) **Patent No.:** **US D924,268 S**
Clymer (45) **Date of Patent:** **** Jul. 6, 2021**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventor: **Erica L. Clymer**, Northampton, PA
(US)

(73) Assignee: **Lutron Technology Company LLC**,
Coopersburg, PA (US)

(**) Term: **15 Years**

(21) Appl. No.: **29/689,734**

(22) Filed: **May 1, 2019**

Related U.S. Application Data

(63) Continuation of application No. 29/629,838, filed on Dec. 15, 2017, now Pat. No. Des. 851,678.

(57) **CLAIM**

The ornamental design for a display screen or portion thereof with graphical user interface, as shown and described.

DESCRIPTION

The sole FIGURE shows a display screen or portion thereof with graphical user interface showing my new design. The peripheral dashed broken lines illustrate a display screen or portion thereof or sheet material, and form no part of the claimed design.

1 Claim, 1 Drawing Sheet
